UNITED STATES PATENT OFFICE.

WILLIE F. MOTTIN, OF NOEL, MISSOURI.

MACHINE-GUN.

1,290,842.

Specification of Letters Patent.

Patented Jan. 7, 1919.

Application filed May 4, 1917. Serial No. 166,387.

To all whom it may concern:

Be it known that I, WILLIE F. MOTTIN, a citizen of the United States, residing at Noel, in the county of McDonald and State 5 of Missouri, have invented certain new and useful Improvements in Machine-Guns, of which the following is a specification.

This invention relates to an improved machine gun and the principal object of the invention is to provide improved means for feeding the cartridges into the gun and to provide improved means for engaging the cartridges from the carrying strip and conveying them into the barrel of the gun and 15 further to provide improved means for discharging the cartridges and removing the cartridges from the gun barrel and ejecting them from the gun.

Another object of the invention is to so 20 construct the means for placing the cartridges in the barrel that the discharging plunger may be carried thereby and moved into and out of an operative position by the same means serving to move the cartridge 25 conveying means.

Another object of the invention is to so 30 construct the cartridge engaging and conveying means that the cartridge will be securely held in engagement therewith until moved out of engagement with the grasping hooks by an abutment plate passing through 35 the breech block.

This invention is illustrated in the accompanying drawings, wherein:—

35 Figure 1 is a longitudinal vertical sectional view through the rear end portion of a machine gun provided with the improved construction.

Fig. 2 is a longitudinal transverse sectional view taken along the line 2—2 of Fig. 1.

Fig. 3 is a transverse sectional view taken along the line 3—3 of Fig. 1.

Fig. 4 is a transverse sectional view taken 45 along the line 4—4 of Fig. 1.

Fig. 5 is a plan view of the cartridge carrying belt or strip.

Fig. 6 is a view in elevation of the improved cartridge carrying belt or strip.

50 This machine gun is provided with a barrel 10 positioned in a jacket 11, the jacket being provided with passages 12 for cooling purposes, it being understood that if desired a suitable cooling fluid may be passed 55 through these passages. This barrel 10 is positioned in front of a chamber or housing

13 formed in two sections connected by the fasteners 14 as shown in Figs. 1 and 2. In the forward end portion of this chamber or housing, there is provided a passage 15 registering with the bore 16 of the gun-barrel and permitting the cartridge to be passed into the gun-barrel. It will be noted that the upper portion of this chamber is also provided with an opening designated as 17 in Fig. 1 for a purpose which will be hereinafter brought out. By having this chamber formed in two sections and connected by the fasteners 14, it may be taken apart easily for purposes of repair and cleaning. 70

Within this chamber there is provided a feeding roller 18 having a supporting shaft or axle 19 rotatably mounted by having one end journaled as shown at 20 and by having its rear end portion passed through the bearing of bracket 21. This feeding roller is provided with teeth 22 fitting into the openings 23 formed in the cartridge carrying belt or tape 24 to feed the tape through the chamber with the side portions of the tape 80 passing between the strips 25 forming the guide for the tape. This tape passing through openings 26 and 27 formed in the sides of the chamber and carries the cartridges 28, the cartridges being held to the 85 tape by a second or auxiliary strip 29 formed of paper or other tearable material. This cartridge carrying belt or tape will be fed transversely through the chamber and as it moves across the same, the cartridges 90 will be removed from the tape by means to be hereinafter described and the tape will then be fed out through the opposite side of the chamber.

In order to drive the roller 18 and operate 95 the discharge means, to be hereinafter described, there is provided a driving shaft 30 rotatably mounted in the chamber and extending transversely therein and beyond the side of the chamber to receive a turning 100 crank, not shown. This driving shaft 30 carries a beveled gear 31 meshing with a beveled gear 32 rigid upon the rear end portion of the driven shaft or axle 19 and it will thus be seen that as this driving shaft 105 30 is rotated, the feeding roller 18 will be rotated to pass the tape or belt 24 through the chamber. A crank shaft 33 is rotatably mounted in the chamber as shown in Fig. 2 and carries a relatively small gear 34 meshing with a large gear 35 rigid upon the driving shaft 30 and through the medium of the 110

gear 34 imparting rotary movement to the crank shaft 33 at a rate relatively faster than the rotation of shaft 30. It will thus be seen that through the rotation of the 5 single driving shaft 30, rotary movement can be transmitted to the shaft 19 and to the crank shaft 33.

The breech block 36 is positioned in the upper portion of the chamber 13 and provided with side ears or arms 37 engaging the tracks 38 to slidably mount the breech block. An extension 39 is formed beneath this block as shown in Fig. 3 and is provided with a passage 40 in which is slidably mounted, the discharging plunger 41 which has its rear end portion pivotally connected with the arm 42 of the latch 43 by fastener 44. A link 45 is connected with the crank 46 of the crank shaft 33 as shown 10 at 47 and is connected with the arm 42 by fastener 44 and it will thus be seen that as the crank shaft rotates, the plunger will be moved longitudinally, the latch swung upon its pivot 48 into and out of the socket 17 15 and the breech block 36 moved longitudinally in the chamber 13. This latch 43 is pivotally mounted in a cutout or pocket 49 formed in the breech block and limited in its swinging movement in one direction by 20 the abutment shoulder 50 and further carries a roller 51 which through engagement with the upper wall of the chamber permits the breech block to slide easily and further permits this latch to easily move 25 into and out of the socket 17. In the side portions of the extension 39 there is provided cutouts forming pockets 52 in which are mounted hooks 53 and 54 engaged by 30 springs 55 to yieldably hold the hooks in position for engagement with the cartridges. It will thus be seen that when the breech block has moved rearwardly to its fullest extent and then moved forwardly, the hooks 35 will engage a cartridge as shown in Fig. 2 and move the cartridge into the position shown in the figure. Immediately upon the cartridge reaching the position shown, the plunger will penetrate the explosive cap of the cartridge and the bullet will be driven 40 from the gun. The breech block will then be drawn rearwardly thus drawing the cartridge out of the barrel. As this breech block moves rearwardly, the abutment plate 56 which is mounted in the chamber and 45 passes through the cutout 57 of the extension 39, will engage the cartridge and swing the same outwardly past their hook 53 thus turning the shell in the direction of the opening 27. The shell will pass out through 55 this opening 27 and the breech block will again move forwardly engaging a fresh cartridge and carrying it into the gun barrel. It will thus be seen that through turning the crank, the cartridges may be fed 60 through the chamber to a position in alignment with the bore of the gun barrel, then engaged by the breech block and moved into the gun barrel and discharged with the latch 43 in the position shown in Fig. 1, to guard against damage to the mechanism 70 from recoil and after the cartridge is discharged, the shell removed from the gun barrel disconnected from the breech block and passed out through the opening 27. It will be further noted that springs are not 75 relied upon for the proper action of this device with the exception of the springs holding the hooks 53 and 54 in the position shown in Fig. 2 and that therefore the device will not quickly get out of order or 80 break.

What is claimed is:

1. A machine gun including a body having a barrel and a chamber to the rear of said barrel, tape supporting strips extending 85 through the chamber in operative relation to side openings formed therein, a driven shaft rotatable in the chamber, a feeding roller carried by the shaft for engaging a cartridge carrying strip supported by the 90 supporting strips and feeding the cartridge carrying strip through the chamber, a breech block slidable in the chamber and provided with means for releasably engaging a cartridge to remove the cartridge from the carrying strip and place the cartridge in the barrel of a gun, discharging means carried by the breech block, a latch for the breech block, a crank shaft rotatable in the chamber, a link connected with the crank shaft 100 and with the latch and discharging means for moving the latch and discharging means into and out of an operating position as the breech block slides in the chamber, and means for imparting rotary movement to 105 the crank shaft and driven shaft.

2. A machine gun comprising a body having a barrel and a chamber to the rear of said barrel, a breech block slidable in the chamber, a discharging plunger slidably carried by the breech block, a latch movably connected with the breech block, cartridge engaging means carried by the breech block, means for feeding cartridges into the chamber including a roller having a rotatably 110 mounted supporting shaft, a crank shaft rotatable in the chamber, a link pivotally connected with the crank shaft and with the latch and discharging plunger, and means for imparting rotary movement to the supporting shaft and crank shaft.

3. A machine gun including a body having a barrel and a chamber to the rear of said barrel, a breech block slidable in the chamber, a discharging plunger slidably carried 115 by the breech block, a latch movably carried by the breech block, means for feeding cartridges into the chamber including a roller and a supporting shaft for the roller, and driving means including a crank shaft hav- 120

130

ing a link extending therefrom and connected with the latch and discharging plunger, rotation of the crank shaft reciprocating the link to move the latch and discharging plunger into and out of an operative position, and reciprocate the breech block longitudinally in the chamber.

4. A machine gun comprising a body having a barrel and a chamber to the rear of said barrel, a breech block slideable in the chamber and provided with cartridge engaging means, means in the chamber for engaging a shell to disengage the shell from the breech block as the block moves rearwardly in the chamber after discharging of the cartridge in the barrel, means for feeding cartridges into the chamber in timed relation to the movement of the breech block, a latch movably connected with the breech block, a discharging plunger carried by the breech block, and means engaging the latch and discharging plunger for moving the same into and out of an operative position as the breech block moves longitudinally in the chamber.

5. A machine gun comprising a body having a barrel and a chamber to the rear of said barrel, a breech block slidably mounted in the chamber, means for feeding cartridges through the chamber in timed rela-

tion to the movement of the breech block, cartridge engaging means carried by the breech block, a discharging plunger and a latch carried by the breech block, a crank shaft rotatably mounted in said chamber, 35 and means extending from the crank shaft and connected with the discharging plunger and latch for moving the latch into and out of an operative position as the breech block moves.

6. A machine gun comprising a body including a barrel and a chamber to the rear of said barrel and communicating therewith, cartridge feeding means in said chamber, a breech block movable in the chamber 45 in operative relation to the feeding means and provided with a latch and a discharging plunger, operating means mounted in the chamber and having connection with the plunger and latch for imparting movement 50 to the breech block and moving the latch and discharging plunger into and out of an operative position.

In testimony whereof I affix my signature in presence of two witnesses.
